UNITED STATES PATENT OFFICE.

ANNA M. CLARKE, OF SCRANTON, PENNSYLVANIA.

SAD-IRON HEATER.

No. 856,223.

Specification of Letters Patent.

Patented June 11, 1907.

Application filed September 19, 1906. Serial No. 335,272.

To all whom it may concern:

Be it known that I, ANNA M. CLARKE, a citizen of the United States, residing at Scranton, in the county of Lackawanna and 5 State of Pennsylvania, have invented certain new and useful Improvements in Sad-Iron Heaters, of which the following is a specification, reference being had therein to the accompanying drawing.

10 My invention relates to improvements in sad iron heaters for use upon cooking or heating stoves provided with removable lids or covers.

15 The object of the invention is to improve and simplify the construction and operation of devices of this character and thereby render the same more efficient.

With the above and others objects in view, the invention consists in the novel construction, combination and arrangement of parts 20 hereinafter fully described and claimed, and illustrated in the accompanying drawings, in which,

Figure 1 is a side elevation of my improved 25 sad iron heater; Fig. 2 is a vertical sectional view through the same; and Fig. 3 is a top plan view.

My improved sad iron heater comprises a hollow drum 1 here shown in the form of a 30 pyramid provided with four sides upon each of which is adapted to be supported a sad iron; but within the scope of my invention the drum may be of any shape and provided with a greater or less number of faces so that

35 any number of sad irons may be simultaneously heated upon it. The heater drum or body 1 is adapted to be placed upon the top of a stove of any description over a pot or lid opening, and projecting from its large lower

40 end is an annular base flange 2 of greater diameter than the ordinary pot or lid openings in stoves. The flange or base 2 rests upon the top of the stove and, in order to prevent lateral displacement of the heater, I form 45 upon the bottom of the base flange 2 a depending annular rib or shoulder 3 which is adapted to enter the opening in the stove top. The smaller and upper end of the heater body or drum 1 is closed and formed with a cen-

50 trally-arranged depression or recess 4 across which is arranged a cross-bar 5. The recess 4 is provided for the reception of a stove lid lifter, the hooked end of a poker, or any similar device which may engage the cross-bar 5 55 and permit the heater to be lifted and re-

moved from the stove while hot without danger of burning one's hands.

In each of the flat inclined faces or sides 6 of the heater body or drum 1 is formed an opening 7, preferably of elliptical form and of less size than the bottom of the ordinary sad iron. Since the construction of each of the sides 6 of the heater, (and all the parts of the invention arranged thereon) is the same, a description of one will suffice for all. A 65 sad iron of any description may be supported upon the outer face of the side 6 by a supporting flange 8 which projects from said side and extends around the lower end and upwardly upon the two sides of the opening 7. The 70 lower or curved portion of the flange 8 is inclined upwardly and inwardly, as seen in Fig. 2, so as to engage the pointed end of a sad iron and more effectively hold the latter upon the side 6. The supporting flange 8 is arranged some distance from the edge of the 75 opening 7 and between said flange and edge upon the outer face of the side 6 are formed small projections 9 which are engaged by the bottom of the sad iron so that the latter is 80 spaced slightly above the side 6 of the heater to permit the heat within the drum or body 1 to pass outwardly under the bottom of the iron and thereby more quickly and effectively heat the latter.

85 Each of the openings 7 is adapted to be closed by four door sections 10, 11, 12, 13. As illustrated in the drawings, they are mounted upon the inner face of the side 6 and are therefore disposed entirely within the 90 body or drum 1. The door sections 10, 11 are similar in shape and are pivoted at their upper ends as at 14. The door sections 12, 13 are also similar in shape and are pivoted adjacent to their upper and outer ends, as at 95 15. The door sections 10 and 12 are connected together by a pivot link 16 which causes them to open and close simultaneously, and the door sections 11 and 13 are similarly connected by a link or rod 16 so 100 that they swing together. The outwardly swinging movement of the door sections is limited by stops 17 in the form of lugs or studs suitably arranged upon and projecting from the inner face of the side 6, as shown in 105 Fig. 2; and the inwardly swinging movement of the door sections is limited by stops 18, 19 also in the form of lugs projecting from the inner face of the side 6 and arranged at the upper and lower ends of the opening 7. 110

Recesses or notches 20, 21 are formed respectively in the door sections 10, 11 and 12, 13 for the reception of the stop lugs 18, 19, as will be readily understood upon reference 5 to Fig. 2. The door sections 10—11—12—13 are so shaped and pivoted that they will swing by gravity to their closed positions and in order to permit these door sections to be swung open by the said iron when it is 10 placed in position upon the side 6 and to hold said door sections open, I provide upon the outer faces of the lower door sections 12—13 the ribs or projections 22. The latter are arranged angularly with respect to each 15 other and inclined downwardly and inwardly. They project outwardly from the outer faces of the sections 12—13 and sufficiently beyond the outer surfaces of the side 6 to receive and support the sad iron. To cause 20 them to more effectively hold the sad iron upon the side 6 they are inclined upwardly and inwardly, as clearly shown in Fig. 1.

It will thus be seen that the weight of the iron supported upon ribs 22 will hold the 25 door sections in their open position and that when the iron is removed the door sections will swing automatically to their closed position. It will be understood that the iron supporting and door operating ribs 22 30 may be used interchangeably with the iron supporting flange 8, since when the iron is supported upon ribs 22 the flange 8 is unnecessary.

From the foregoing description, taken in 35 connection with the accompanying drawings, it is thought that the construction, operation and advantages of my invention will be readily understood without a more extended explanation.

40 While I have shown and described a preferred embodiment of my invention, it will be understood that I do not wish to be limited to the precise showing herein set forth since various changes in the form, proportion 45 and minor details of construction may be resorted to without departing from the spirit and without sacrificing any of the advantages of the invention, as defined by the appended claims.

50 Having thus described my said invention, what I claim as new and desire to secure by Letters Patent of the United States, is

1. A heater of the character described, comprising a hollow body having an opening in one of its sides, means for supporting a sad iron upon the outer face of said side above said opening, and a self-closing door located upon the inner face of said side for closing said opening.

60 2. A heater of the character described comprising a hollow body having flat inclined sides formed with openings of less size than the bottom of a sad iron, a sad iron supporting flange projecting outwardly from each of said sides and arranged around the

bottom and sides of each of said openings, projections arranged upon the outer faces of said sides between the edges of said openings and said iron supporting flanges for spacing the bottoms of sad irons above the sides of 70 the heater body and doors located on the inner faces of said sides for closing said openings, substantially as shown and for the purpose set forth.

3. A heater of the character described 75 comprising a hollow body formed with flat inwardly and upwardly-inclined sides each of which is provided with a centrally-arranged opening of less size than the bottom of a sad iron, said body also having a 80 closed top formed with a depression, a rigid cross-bar arranged across said depression and formed integral with said body, a base flange projecting from the open bottom of said body, and formed upon its bottom with 85 an annular shoulder to enter the opening in a stove top, a sad iron supporting flange projecting outwardly from each of the sides of the heater body and arranged around the 90 bottom and sides of the openings in the sides of the heater body, and projections arranged upon the sides of the heater body between the edges of their openings and said iron supporting flanges for spacing the bottoms of sad irons above the sides of the heater 95 body, substantially as shown and for the purposes set forth.

4. A heater of the character described comprising a hollow body formed with flat inwardly and upwardly-inclined sides each 100 of which is provided with a centrally-arranged opening of less size than the bottom of a sad iron, said body also having a closed top formed with a depression, a cross-bar arranged in said depression, a base flange 105 projecting from the open bottom of said body, and formed upon its bottom with an annular shoulder to enter the opening in a stove top, a sad iron supporting flange projecting outwardly from each of the sides of the 110 heater body and arranged around the bottom and sides of the openings in the sides of the heater body, projections arranged upon the sides of the heater body between the edges of their openings and said iron supporting 115 flanges for spacing the bottoms of sad irons above the sides of the heater body, and movable doors located upon the inner faces of said sides for closing the openings in the sides of the heater body.

5. A heater of the character described comprising a hollow body having an opening in one of its sides, means for supporting a sad iron above the opening in said side, and a door located within the body for closing said 125 opening.

6. A heater of the character described comprising a hollow body having an opening in one of its sides of less size than the bottom of a sad iron, means for supporting a sad iron 130

- above the opening in said side, and movable doors located upon the inner face of said side for closing said opening.
7. A heater of the character described, comprising a hollow body having an opening in one of its sides, means for supporting a sad iron above the opening in said side, a swinging door mounted upon the inner face of said side and adapted to close said opening, and a projection upon said door extending through the opening in said side of the body and adapted to be engaged by a sad iron for opening said door, substantially as described.
8. A heater of the character described, comprising a hollow body having an opening in one of its sides, means for supporting a sad iron above the opening in said side, a door pivoted upon the inner face of said side and adapted to swing downwardly by gravity to close said opening, a stop for limiting the swinging movement of said door, and a projection upon said door extending through the opening in the side of said body and adapted to be engaged by a sad iron for opening said door, substantially as described.
9. A heater of the character described, comprising a hollow body having an opening in one of its sides, means for supporting a sad iron above the opening in said side, pairs of door sections pivoted upon the inner face of said side and adapted to swing downwardly by gravity to close the opening in said side, links connecting the door sections of each pair to cause them to swing simultaneously, and projections upon certain of said door sections extending through the opening in said side and adapted to be engaged by a sad iron for opening said door sections, substantially as described.
10. A heater of the character described, comprising a hollow body having an opening in one of its sides, means for supporting a sad iron above the opening in said side, a pair of oppositely swinging doors pivoted upon the inner face of said side and adapted to close the opening therein, and oppositely inclined projections upon said doors extending through the opening in said side of the body and adapted to be engaged and move apart by a sad iron for opening said doors, substantially as described.
11. A heater of the character described comprising a hollow body having an opening in one of its sides, and a self-closing door for said opening adapted to be held open by an iron supported upon said side of the body and above said opening.
12. A heater of the character described comprising a hollow body having an opening in one of its sides, and a gravity closing door adapted to be held open by a sad iron supported upon said side of the body and above said opening.
13. A heater of the character described comprising a hollow body having an opening in one of its sides, a swinging door for said opening mounted to swing normally to its closed position, and means upon said door to be engaged by a sad iron for opening said door and for supporting said iron above the opening in the side of the body.
14. A heater of the character described comprising a hollow body having an opening in one of its sides, gravity closing doors located upon the inner faces of said side for closing said opening, and means upon said doors for engagement by a sad iron for opening said doors and supporting said iron above the opening in the side of said body.
15. A heater of the character described comprising a hollow body having an opening in one of its sides, gravity closing doors for closing said opening, and projections upon said doors for engagement by a sad iron for opening said doors and supporting said iron above the opening in the side of said body.
16. A heater of the character described comprising a hollow body having an opening in one of its sides, pairs of pivotally mounted door sections connected for simultaneous swinging movement and adapted to swing to their closed position by gravity, and inclined projections upon certain of said door sections adapted to be engaged by and to support a sad iron, substantially as shown and described.
- In testimony whereof I hereunto affix my signature in presence of two witnesses.
